DESIGN FOR A SHOE

Fred Pfaeffle, Brooklyn, N. Y.

Application August 19, 1937, Serial No. 71,199

Term of patent 3½ years

To all whom it may concern:

Be it known that I, Fred Pfaeffle, a citizen of the United States of America, residing in Borough of Brooklyn, county of Kings, city and State of New York, have invented a new, original, and ornamental Design for a Shoe, of which the following is a specification, reference being had to the accompanying drawing, forming part thereof.

Fig. 1 is a plan view of the shoe showing my new design.

Fig. 2 is a perspective view thereof.

I claim:

The ornamental design for a shoe, substantially as shown.

FRED PFAEFFLE.
